UNITED STATES PATENT OFFICE

2,031,514

ELECTRIC CIRCUIT INTERRUPTER

Carl Thumim, Philadelphia, Pa., assignor to
General Electric Company, a corporation of
New York

Application July 3, 1934, Serial No. 733,563

2 Claims. (Cl. 200—146)

5 My invention relates to electric circuit interrupters and has for its principal object the provision of an improved circuit interrupter in which "burning" of the contacts during interruption of heavy currents is minimized and which has increased interrupting capacity and comparatively high operating speed.

10 The interruption of high tension power circuits by oil circuit breakers, for example, is often attended by excessive "burning" of the contact material which is usually copper. The burning or melting away of the contact material by heavy arcs may after a number of operations necessitate taking the breaker temporarily out of service and installing new contact structure. Furthermore, in order to compensate for burning comparatively large masses of contact material are used, thereby increasing the inertia of the moving parts and the cost of the breaker.

15 20 In accordance with my invention, burning is greatly minimized by means of a substantially non-inductive resistance which is inserted in series in the circuit to be interrupted upon separation of the main current-carrying contacts, and 25 the circuit breaker structure is simplified and adapted for high speed operation by incorporating said resistance in the stationary contact assembly.

25 30 My invention will be more fully set forth in the following description referring to the accompanying drawing, and the features of novelty which characterize my invention will be pointed out with particularity in the claims annexed to and forming a part of this specification.

35 40 Referring to the drawing, Fig. 1 is a diagrammatic illustration of a circuit interrupter embodying my invention, and Fig. 2 is an elevational view, partly in section, of coacting contact structure of one pole of an oil circuit breaker embodying my invention.

45 50 There is diagrammatically illustrated in Fig. 1 a circuit interrupter comprising a pair of fixed contacts 1 and 2 adapted to be interconnected by a movable conducting bridging member 3 in the closed circuit position. The stationary contacts are connected in the circuit to be interrupted by conductors 4 and 5, respectively. For the purpose of minimizing burning of the contact material when the bridging member 3 is lowered 55 during the circuit opening operation, each pole of the circuit interrupter is provided with a pair of substantially non-inductive resistances 6 and 7 suitably connected between a main circuit conductor, as 5, and an auxiliary fixed contact 8.

55 In the present instance the resistances 6 and 7

are shown as connected in parallel with each other, it being understood, of course, that the amount of resistance may be varied in accordance with the interrupting requirements of the circuit breaker. The auxiliary contact 8 is adapted to coact in sliding engagement with the contact 9 electrically connected to and carried by the bridging member 3. The contacts 9 are likewise adapted to engage the stationary contacts when the bridging member is elevated for completing the circuit.

5 10 15 The contacts 9 may likewise engage the contacts 8 in the closed circuit position, the aforesaid contacts being in sliding engagement during the initial circuit opening movement and after separation of the stationary contacts and bridging member. In the position illustrated the bridging member 3 may be considered as moving downwards to the open circuit position, the main current-carrying contacts having separated and 20 the resistances 6 and 7 now being in series in the circuit through the contacts 8 and 9. Upon separation of the main current-carrying contacts little or no arcing will take place as the circuit is not open, the current, on the other hand, being materially decreased by the insertion of resistances above described. Accordingly, upon final separation of the contacts 8 and 9 the current has been appreciably reduced so that 25 interruption of the circuit is not only more easily effected but is accompanied by much lower intensity.

30 35 It will likewise be apparent that burning of the contact material due to closing of the circuit interrupter on heavy load currents is also minimized in view of the fact that the contacts 8 and 9 are the first to engage. The resistance so inserted decreases the current to such an extent that subsequent closing of the main current-carrying contacts is not accompanied by burning.

40 45 Referring more particularly to Fig. 2 which illustrates the detailed structure of one pole of the circuit interrupter diagrammatically illustrated by Fig. 1, the stationary contact structure 2 comprises a contact adapter 10 of conducting material which is electrically connected to the lower end of the circuit conductor stud 5 and which carries at its lower end finger contacts 11 arranged to be engaged by the movable bridging member 3. The finger contacts 11 may be of any 50 suitable and well known type and are arranged in pairs so as to be engaged and spread apart by the wedge-shaped contact portion 9 of the bridging member.

45 55 For the purpose of simplifying the stationary

contact assembly, the adapter 10 is provided with aperture or bores 12 extending therethrough in which the resistance elements 6 and 7 are disposed. Each resistance element or unit may comprise a resistance wire 13 wound on a cylinder 14 of insulating material, one terminal of each unit, as 6, being electrically connected as at 15 to a conducting plate 16 secured to the adapter and closing one end of each aperture 12, and the other terminal being connected as at 17 to conducting strips 18. Each resistance element, except for terminal 15, is insulated with respect to the adapter 10 by any suitable means as the concentric insulating cylinders 19 which are mounted within the aperture 12. The terminal conducting strips 18 are mounted on an insulating plate 20 which is in turn secured, as at 21, to the adapter. The insulating plate 20 is provided with apertures 22 in alignment with apertures 12 for receiving one end of each resistance element.

20 The conducting strips 18 terminate in the auxiliary contact 8 which is engaged by the coacting auxiliary member 9' of the bridging contact portion 9 during a part of the travel of the bridging member. The auxiliary contact 8 is not only electrically connected to the resistance elements through the conducting strips 18 but is biased into resilient contact engagement with member 9' thereby.

30 Accordingly, upon either circuit opening or circuit closing movement the bridging member 3 when in the lower dotted line position shown is connected with the auxiliary contacts 8 so that the resistances 6 and 7 are connected in series 35 in the circuit to be interrupted, resulting in improved operation which prolongs greatly the operating life of the portions of the contact structures 9 and 11 and in addition increases the interrupting capacity of the circuit interrupter by reason of the fact that arcing is more readily 40 extinguished. The operating speed of the breaker is likewise comparatively high since the mass of the moving elements may be reduced by the amount of copper generally lost by burning, the 45 additional structure associated with my inven-

tion being incorporated in the stationary contact assembly.

It should be understood that my invention is not limited to specific details of construction and arrangement thereof herein illustrated, and that 5 changes and modifications may occur to one skilled in the art without departing from the spirit of my invention.

What I claim as new and desire to secure by Letters Patent of the United States, is:—

10 1. An electric circuit interrupter comprising coacting stationary and movable contact structure, said stationary structure including a lead-in conductor, a block of conducting material forming an adapter connected to said lead-in conductor, 15 main and auxiliary contacts supported by said block, and a resistance coil positioned in a recess formed in said block, one terminal of said coil electrically connected to said block and the other terminal electrically connected to said auxiliary 20 contact, said movable contact structure likewise including main and auxiliary contacts for coacting respectively with the aforesaid stationary main and auxiliary contacts.

25 2. An electric circuit interrupter comprising coacting stationary and movable contact structure, said stationary structure including a lead-in conductor, a block of conducting material forming an adapter connected to said lead-in conductor, main contacts supported by and electrically connected to said block, a resistance coil positioned 30 in a bore extending transversely through said block, a plate of conducting material secured to said block for closing one end of said bore, one terminal of said coil electrically connected to said 35 plate, a plate of insulating material secured to said block closing the other end of said bore, an auxiliary contact mounted on said insulating plate and electrically connected to the other terminal of said coil, said movable contact structure 40 including main and auxiliary contacts for coacting respectively with said stationary main and auxiliary contacts.

CARL THUMIM. 45
